UNITED STATES PATENT OFFICE.

CLARENCE WARNER, OF DAYTON, OHIO, ASSIGNOR TO DELCO-LIGHT COMPANY, OF DAYTON, OHIO, A CORPORATION OF DELAWARE.

PUMP.

Application filed May 3, 1926. Serial No. 106,806.

This invention relates to improvements in pumping apparatus of the suction type.

It is among the objects of the present invention to lubricate the moving elements of the pumping apparatus by the fluid delivered by the pump.

Further objects and advantages of the present invention will be apparent from the following description, reference being had to the accompanying drawings, wherein a preferred form of embodiment of the present invention is clearly shown.

In the drawings:

Fig. 1 is a part sectional view taken along the line 1—1 of Fig. 2.

Fig. 2 is a part section taken along the line 2—2 of Fig. 1.

Fig. 3 is a side elevation of the pumping apparatus.

20 Referring to the drawings numeral 20 designates the container or crankcase provided with an open end 21 adapted to be closed by means of a cover plate 22 held in position by studs 23. Container 20 has a flange 24 which is adapted to fit on a flange 25 provided on the tank 26. Flanges 24 and 25 are held together by means of studs 27.

25 The tank 26 has a pipe 28 which forms communication between the inside of the container 20 and tank 26. Another pipe 29 leading from the tank 26 connects with the various pipes not shown through which fluid is delivered from the tank 26 to various outlets, not shown.

30 A lug 30 formed on the container 20 has a passage 31 communicating with the inside of said container, said passage being screw-threaded to receive a coupling 32 to which is secured the pressure switch member 33.

35 This pressure switch member 33 is controlled by pressure within the container 20 and is adapted, in turn, to control the operation of the electric motor 34 which is mounted on the upper surface 35 of container 20.

40 The motor 34 includes a drive shaft 36, to the outer end of which is secured a driving pulley 37 shown in the present drawings to be of the V-type. A corresponding V-type pulley 38, of greater diameter however, is secured to the drive shaft 39 in any suitable manner. A V-type belt 40 connects the driving pulley 37 with the driven pulley 38.

45 Within the container 20 there is provided a tubular portion 45 preferably formed in-

tegral with said container. This tubular portion is open at both ends and has an aperture 46 communicating with the inside of the container. At the edge of this aperture nearest the inner open end of the tubular portion there is provided an upwardly extending partition 47 which terminates below the ceiling 20^a of the container 20. This partition forms chambers 48 and 49 inside the said container, said chambers being in communication with each other by means of the passageway 50 formed by the space between the upper edge of the partition 47 and the ceiling 20^a of the container.

55 The outer end of the tubular portion 45 is provided with screw threads on its interior surface for receiving the valve cage 51. This valve cage is provided with passages 52 and 53 formed on opposite sides of a central lug 54. Passage 53 communicates with a passage 55 formed in the tubular portion 45, said passage having a plug 56 provided therein. Passage 52 communicates with the intake port 57, formed by housing extension 58 secured to or formed integral with the end wall of the container 20. Pipe 59 is connected to the intake port 57, said pipe 59 leading to any desired source of fluid to be pumped, said source not being shown in the present drawings.

60 The central lug 54 has a screw-threaded recess which receives the pin 60, said pin supporting a collar 61 at its free end. The valve cage is provided with an annular valve seat 62 formed about passages 52 and 53. The end of the central lug 54 is flush with the annular valve seat 62 and forms the inner section of the valve seat. Engaging with this valve seat is a disc valve 63 loosely carried by the pin 60 and held against its seat by means of a spring interposed between the collar 61 and the valve.

65 A cylinder 65 is provided in the tubular portion 45, the one end of the cylinder lying in spaced relation with the valve cage 51 while the other end of the said cylinder extends into the container 20 as shown in Fig. 1. The cylinder 65 is provided with a plurality of apertures 66 adjacent the inner edge of the aperture 46 of tubular portion 45.

70 The cylinder 65 includes a piston 70 which comprises a cross head member 71 and a piston head comprising an assembly of various elements to be described. The

cross head 71 includes a cylindrical portion 72 of lesser diameter than the inside diameter of cylinder 65, said cylindrical portion being in turn provided with spaced shoulder portions 73 and 74 arranged about its peripheral surface. A bearing bushing 75, surrounds the cylindrical portion 72 of said cross head, said bearing bushing being interposed between the spaced shoulder portions 10 73 and 74. This bearing bushing slidably supports the cross head in the cylinder 65. In pumps used for delivering water it is preferable to use leather for the bearing bushing inasmuch as water will tend to lubricate the same and keep it in good condition.

Extending forwardly toward the valve cage 51 there is another cylindrical portion 76, of lesser diameter than the portion 72, 20 secured to, or as shown in the drawings, formed integral with the said larger cylindrical cross head portion 72. This smaller cylindrical portion 76 is closed at its forward end by means of wall 77. Extending 25 forwardly from the portion 76 and formed integral therewith is a spider portion including oppositely disposed arms 78, the outer edges of which are spaced from the cylinder 65. These arms 78 support a 30 ring 79 of substantially lesser diameter than the cylinder 65, said ring being screw-threaded on its interior surface for receiving a hollow sleeve 80. Hollow sleeve 80 has an outwardly extending flange 81 at 35 its forward end by means of which the sleeve is adapted to act as a clamping element for the leather cup washers 82 and 83 which form the bearing elements of the piston head. The washer 83 is clamped between 40 the ring 79 and a spacer ring 84 which surrounds the sleeve 80 while the cup washer 82 is clamped between the spacer ring 84 and the flange 81 of the sleeve 80. Thus it may be seen that the piston head 45 comprises the flanged sleeve 80, cup washers 82 and 83 with their interposed spacer ring 84 and the ring 79 which is secured to the cross head 71 by means of the spider arms 78.

The edge of the inner end of sleeve 81 lies 50 adjacent the spider arm 78 and forms a seat for the valve 86 which is loosely carried on a stud 87 carrying a central guide member 88 provided in the sleeve 80. The valve 86 is held against its seat by means of a spring 55 interposed between the valve seat and the end wall 77 of the cross head 71, said valve being kept in alignment with its seat by means of the guide member 88 which is in the form of a spider to permit fluid to pass 60 through the sleeve.

Due to the cross head portion 76 being of lesser diameter than the interior of cylinder 65 a space or chamber 89 is provided in the cylinder. The cross head portion 72 65 and the piston head are so spaced that in

any position of the piston 70 during its stroke the apertures 66 of the cylinder 65 will be in communication with chamber 89.

A wrist pin 90 is carried in the cross head portion 72. The one end of the connecting rod 91 is connected to said wrist pin 90. The opposite end of the connecting rod 91 has a bearing ring or strap 92 which fits about a fibrous bearing bushing 93, preferably of leather, which is carried by the eccentric 94 between spaced shoulders in a similar manner as the bearing bushing on the cross head. Eccentric 94 is mounted on the end of the drive shaft 39 that extends through container 20.

Referring to Fig. 2, the method of supporting the drive shaft 39 is clearly illustrated. A journal box 95 is provided having a flange 96 apertured to receive studs 97 by means of which the journal box is secured to the one side of the container or crankcase 20. The journal box 95 carries bearing bushings 98 in which is journaled the shaft 39. The bushings 98 are split and thereby permit a ring 99 to float on the drive shaft 39 between said bearings, said ring being of sufficient diameter so that its lower portion will dip into the lubricant 100 provided in a lubricant pocket 101 formed integral with the journal box 95. The hub of the pulley 38 has an oil groove 102 which substantially prevents any oil from finding its way to the aperture in the journal box through which the hub of the pulley 38 extends.

The surface of the flange 96 adjacent the side wall of the crankcase 20 is provided with an annular protuberance 103. A diaphragm 104 surrounds the shaft 39 and is interposed between the protuberance 103 and the surface of the crankcase 20, said diaphragm being clamped tightly therebetween when the studs 97 are drawn up to clamp 105 the journal box 95 against the crankcase. A sealing ring 105 surrounding shaft 39 is secured to the diaphragm 104 by means of soldering or welding, said sealing ring being recessed to receive a bearing ring 106 made up of any suitable lubricant containing material. The sealing ring 105 is positioned in the aperture formed in the side of the crankcase 20 and which is closed by the diaphragm 104.

The shaft 95 has a flange 107 whose inner surface engages with the bearing ring 106. The end of the shaft 95 which lies adjacent the inner wall of the crankcase or container 20 is engaged by the convex surface of a washer 108 provided in a recessed nut 109 screw-threaded in the passage of a lug portion 110 formed on the one side of the container or crankcase 20. A spring 111 is interposed between the end 112 of the recessed nut 109 and the washer 108, said spring tending to exert a pressure upon the washer 115 120 125 130

whereby the shaft 39 will be forced to the right as regards Fig. 2. Pressure of the spring 111 against the shaft 39 will force the flange 107 against the bearing ring 106. A seal will thus be provided which will prevent lubricant 100 from passing along the shaft 39 and entering into the container 20 and also the fluid in container 20 will be prevented from entering the lubricant pocket 101.

When the motor 34 is operating, the pulley 38 will be rotated thereby causing operation of the eccentric 94. Operation of the eccentric 94 will reciprocate the piston in the cylinder 65.

On the stroke of the piston to the right as regards Fig. 1 fluid will be drawn through the pipe 59 into port 57, thence through passage 52, said fluid then opening the valve 63 against the effect of its spring to hold it closed, entering the cylinder 65 on the side of the piston opposite the cross head 71. This movement of the piston will cause the cross head 71 to exert a pressure upon the fluid in the container 20 thereby tending to compress the air in said container and thus build up a pressure in the container to force fluid from tank 26 when an outlet is opened.

On the reverse stroke of the piston or to the left as regards Fig. 1 the piston will exert a pressure on the fluid in the intake chamber of the cylinder or more specifically the chamber between the valves 63 and 86, thus closing the valve 63 and opening the valve 86. The fluid will now pass from the chamber between said valves 63 and 86, past the valve 86 into the space 89. The cubical contents of space 89 when the piston is at the extreme right position being substantially less than the cubical contents of the space between the valves 63 and 86 more fluid will be forced past the valve 86 than said space 89 may contain, thus a greater portion of this fluid will be forced through the aperture 66 of the cylinder 65 into the chamber 48 of the container 20. Continued operation of the pump will build up a pressure in the container 20 which, when it has reached a proper value will operate the pressure switch element 33 to disconnect the motor 34 from the source of current thus causing it to become inoperative. However, as soon as the pressure in the container 20 reaches a proper low level, to be determined, the pressure switch element 33 will again be operated to connect the motor 34 and institute the pumping operation.

As has been mentioned before the working portions of the pump including the cup washers 82 and 83 of the piston, the bearing bushing 75 of the cross head and the bearing bushing 93 of the eccentric and connecting rod are of such a material preferably leather for water pumps that the fluid within the container or crankcase 20 will keep the same

well lubricated, thereby eliminating the necessity of providing separate lubricating systems for each of these elements.

The provision of the partition 47 will maintain a fluid level in the chamber 48 of the container 20 regardless of the exhaustion of fluid in both the container chamber 49 and tank 26 thereby maintaining a priming medium for the valves 86 and 63.

A valve 120 is provided in connection with the chamber between the valves 63 and 86 whereby air may be supplied to the container 20 when the same becomes water logged. A cap 121 is provided in the passageway communicating with the intake port 57 for purposes of priming said intake port when it becomes necessary.

While the form of embodiment of the present invention as herein disclosed, constitutes a preferred form, it is to be understood that other forms might be adopted, all coming within the scope of the claims which follow.

What is claimed is as follows:

1. A pump comprising, in combination, a container for receiving fluid under pressure; a cylinder associated with said container; a piston in said cylinder for forcing fluid into said container; a cross head in said container adapted to be lubricated by the pumped fluid; means for connecting the piston and cross head, and means in said container for actuating said cross head.

2. A pump comprising, in combination, a container for receiving fluid under pressure; a cylinder in said container; a piston operating in said cylinder, an intake including a valve, adapted to communicate with said cylinder; a valved portion in said cylinder adapted to deliver fluid into said container; a cross head in the cylinder; means for connecting the piston and cross head; a cross head reciprocating member in said container; and a drive shaft extending into the container for operating said member.

3. A pump comprising, in combination, a container for receiving fluid under pressure; a cylinder in said container; a valved inlet for said cylinder; a piston in the cylinder adapted to deliver fluid into said container; a cross head in the cylinder; means for connecting the piston with the cross head, said means being of substantially lesser diameter than the cylinder whereby a space is provided in the cylinder between the piston and cross head; an outlet port in the cylinder so constructed and arranged that it will always communicate with the said space; a piston reciprocating member in the container; and a drive shaft extending into the container for operating the reciprocating member.

4. A pump comprising, in combination, a container for receiving fluid under pressure; a tubular portion in said container; a partition in said container providing two chambers, said partition being so constructed and

arranged as to permit communication between the two chambers, adjacent the upper portion of the container; a cylinder in said tubular portion; a reciprocating member in 5 said cylinder adapted to deliver fluid into said container; and means in the one chamber of the container for operating the reciprocating member.

5. A pump comprising, in combination, a 10 container for receiving fluid under pressure; a tubular portion in said container; a partition in said container providing two chambers, said partition being so constructed and arranged as to permit communication be- 15 tween the two chambers, adjacent the upper portion of the container; a cylinder in said tubular portion and having an outlet port communicating with the one chamber of the container; a piston in said cylinder; and an 20 eccentric in the other chamber of the container for reciprocating the piston.

6. A pump comprising, in combination, a container for receiving a fluid under pressure; a cylinder in said container; a piston 25 in said cylinder, adapted to deliver fluid, under pressure, into said container; a cross head in said cylinder, and attached to the piston, said cross head having a bearing bushing of fibrous material engaging the 30 cylinder; and means in said container for reciprocatively operating the cross head.

7. A pump comprising, in combination, a container for receiving a fluid under pressure; a cylinder in said container; a piston 35 in said cylinder, adapted to deliver fluid, under pressure, into said container; a cross head in said cylinder, and attached to the piston, said cross head having a leather bearing bushing engaging the cylinder; and 40 means in said container for reciprocatively operating the cross head.

8. A pump comprising, in combination, a container for receiving a fluid under pressure; a cylinder in said container including 45 a piston and cross head for said piston; a connecting rod attached to said cross head, and provided with a bearing ring; an eccentric mounted on the end of a drive shaft adapted to actuate said eccentric; and a 50 bearing bushing of fibrous material on said eccentric and fitting in the bearing ring of the connecting rod.

9. A pump comprising, in combination, a container for receiving a fluid under pres-

sure; a cylinder in said container, including 55 a piston and cross head for said piston; a connecting rod attached to said cross head, and provided with a bearing ring; an eccentric mounted on the end of a drive shaft adapted to actuate said eccentric; and a 60 leather bearing bushing on said eccentric and fitting in the bearing ring of the connecting rod.

10. A pump comprising, in combination, a 65 container; a pump in said container for delivering fluid to said container, said pump including a cylinder and a piston in said cylinder; a cross head in the cylinder, connected to said piston and including spaced shoulder portions arranged about its periphery; and a leather bearing bushing surrounding the cross head and interposed between the shoulder portions, said leather bearing bushing engaging the cylinder wall 70 whereby the cross head is slidably supported 75 in said cylinder.

11. A pump comprising, in combination, a container; a pump for delivering fluid to said container; pump operating mechanism within said container, said mechanism including a connecting rod provided with a bearing ring; an eccentric in said container for operating the connecting rod, said eccentric having spaced shoulder portions arranged about its periphery; and a leather bearing bushing surrounding said eccentric and interposed between the shoulder portions of the eccentric and the eccentric and bearing ring, said bearing bushing being adapted to be lubricated by the fluid in the container. 80 85 90

12. A pump comprising, in combination, a container; a pump in said container and adapted to deliver fluid to said container; pump operating mechanism in said container and adapted to be lubricated by the fluid in 95 said container; a drive shaft extending into said container for driving the pump operating mechanism; a lubricant containing journal box for said shaft, associated with said container; and a diaphragm sealing 100 member surrounding the shaft and clamped between the journal box and the container, providing a sealing partition between the container and the journal box.

In testimony whereof I hereto affix my 105 signature.

CLARENCE WARNER.
